SINK CONSTRUCTION

Vincent R. O'Brien, St. Paul, Minn.

Application November 8, 1943, Serial No. 509,515

2 Claims. (Cl. 4—187)

This invention relates to improvement in sink construction where it is desired to provide a means of forming integral with the sink a garbage hopper. This hopper is formed in the sink proper separate and spaced from the sink drain opening. Thus, I provide a separate and distinct hopper means integrally formed with the sink and yet not connected with the regular drain so that the water drain from the sink proper does not pass through the garbage or the waste material discharged in the hopper.

Some of the advantages of my sink construction are ease of disposal of garbage and cleanliness; the garbage never being exposed in the sink; also the bucket in the hopper is larger than most metal baskets used in sinks.

A further feature resides in providing a hopper associated with the sink water faucet which permits the directing of water directly from the faucet on to the garbage put in the bucket in the opening. Thus, the water washes down virtually 50% of the garbage or that portion thereof which readily passes through the openings in the bucket. The openings in the bucket will be of a size to prevent any material which passes through the same from clogging the sink trap or sewage disposal means. Thus, the capacity of the bucket in the hopper is increased by that portion of the garbage which will pass or can be washed away.

It is also a feature to provide the garbage disposal hopper separate from the regular drain in the sink as it provides a means of preventing the acids from vegetables and fruits from destroying the enamel in the bottom of the sink such as is the case where garbage is maintained in a basket in the sink until it is disposed of, and means of providing a separate hopper in the sink whereby none of the acids are allowed in the sink but the vegetable and fruit garbage is put directly into the garbage hopper.

A further feature resides in providing a sink construction as herein set forth which permits the scraping of dirty dishes directly into the hopper with running water available from the sink faucet, thereby providing a more sanitary sink construction.

Further, this integral hopper with the sink proper prevents any cracks where dirt can lodge and keeps the sink basin clean at all times.

It is also a feature to provide my sink with the hopper connected with a garbage basket or container placed in the outside wall of the building with the drain leading therefrom into the regular sewage disposal system and wherein the garbage bucket may be removed from the outside of the

building by the garbage collector. This provides a means of disposal of the garbage without going out of doors.

My sink construction provides a means of receiving a mechanical garbage disposal, a vise operated by an electric motor to grind up all the larger particles of garbage so that the same may be passed directly into the sewage system. Any of these means of disposal of garbage may be adapted to be connected to my sink, thus to provide a sanitary and practical means of disposing of garbage and the like, permitting the use of hot or cold water directly to the hopper from the sink faucet or spray and keeping the sink clean and tidy at all times.

In this manner I provide three distinct types of garbage disposal, namely, the bucket type positioned in the hopper formed integral in the sink body, a mechanical garbage disposal device and the bucket in the outside wall of the building where the garbage collector can have easy access to the same to pick up the garbage and remove the same. It is apparent that this outside wall type of garbage disposal means with the water drain leading into the sewage disposal system from the bottom of the bucket compartment permits a large proportion of the garbage to be washed away into the sewage system of the building, thus not requiring the emptying of the garbage bucket as often as if a large portion of the garbage were not washed into the sewage system.

These several means of disposing of garbage keeps the main sink enamel finish in better condition, permitting the enamel to wear longer and stay brighter and cleaner, and, in fact, retain that original gloss or luster longer.

These features, together with other details and objects, will be clearly defined.

40 In the drawings forming a part of the specification:

Figure 1 is a plan view looking into the sink.

Figure 2 is a partial sectional view showing one form of garbage disposal to which my sink is adapted.

Figure 3 is an enlarged sectional detail of a position of my sink showing the drain connected to the hopper as used in Figure 2.

Figure 4 is a side elevation showing the manner in which my sink may be used with a mechanical garbage disposal device which is electrically operated.

Figure 5 illustrates the side elevation of another manner in which my sink may be used.

Figure 6 is an enlarged sectional detail show-

ing the manner of use as illustrated in Figure 5 of my sink, only a portion of the sink proper being illustrated.

Figure 7 illustrates a perspective view of a sink where my integral hopper construction is employed for garbage disposal.

Figure 8 is a small plan view of an alternative construction.

Figure 9 is a small plan view of an alternative construction.

The sink 10 may be of any ordinary construction provided with a water drain 11 having the usual screen 12 over the same and wherein the well of the sink is open and may be used in the usual manner.

The sink is provided with a swinging faucet outlet 13. The faucet may be of any suitable form and the drawings merely illustrate a form which may be desirable. However, it will be apparent that any faucet with a swinging outlet such as 13 which will swing from one side to the other of the sink is desirable. The sink is also provided with a cold water valve 14 and a hot water valve 15. Further, the sink may be provided with a spray 16 having a flexible connection and which is connected to the hot and cold water outlets so that the spray may be used in place of the outlet 13 when it is desired.

It is a feature to provide the sink 10 with an integral hopper A and a hinge cover 17 for the same. This hopper A may be in a form which projects or bows out into the well of the sink 10 as illustrated in Figures 1 and 3, or the hopper A may be formed integral with the body of the sink 10, but outside of the well thereof as illustrated in Figures 2, 4, 5 and 6.

The sink may be also formed with a cabinet construction as illustrated in Figure 7. However, the hopper A is formed as an integral part thereof and is adapted to receive any accumulation of garbage rather than having the garbage in the well of the sink or connected with the drain 11.

The hopper A is formed with a lower flange 18 which permits my sink to be used in several different ways to dispose of the garbage discharged into the hopper A.

One form of disposal of garbage I have illustrated in Figures 2 and 3 wherein a drain pipe 20 is connected to the flange 18 with a gasket 21 between the flange 18 and the flange of the drain pipe 20. The drain pipe 20 is adapted to discharge the garbage from the hopper A into a bucket 22 which is positioned in the wall 23 of the building. The bucket 22 may be preferably formed like a basket or like the opening in the bottom thereof so that any water directed into the hopper A and passing through the pipe 20 will pass through the bucket to carry the garbage into the bucket and to wash any particles of garbage into the sewer system through the drain passageway 24 and automatically connecting with the drain pipe 25 which leads from the drain 11 of the sink 10. Suitable traps 26 are provided for sanitation. An outside door 27 normally closes the bucket compartment 28 in the wall of the building 23.

Still a further manner of using my sink with the garbage hopper illustrated in Figure 4 where I provide an electrically operated grinding means B for grinding the garbage as it is discharged into the hopper A and discharging the same through the pipe 29 into the regular drain 25 leading from the drain opening 11 of the sink 10.

I have illustrated still another manner in which

my sink 10 may be used with its garbage hopper A such as illustrated in Figures 5 and 6. In this use of my sink 10 with a garbage hopper A, I employ a wire basket 30 positioned in the hopper A and with the lower end of the hopper connected by the drain pipe 31 to the regular drain 25 from the sink 10. In this use of the hopper A with the sink 10, the wire basket receives the garbage in the basket 30 and water from the outlet 13 or the spray 16 may be directed over the garbage in the basket 30 so as to reduce the garbage bulk to a minimum and to wash any part of the garbage into the drain 25.

With this means of garbage disposal, a simple basket 30 collects the garbage bulk which will not wash down the drain and may be carried out when desirable.

In each of the different forms of disposing of the garbage illustrated, the hopper A is employed as integral with the body of the sink 10 and by means of the flange 18, the various different drains of disposal of garbage may be attached thereto. In each case it is apparent that the hopper is separate from the sink body although it is an integral part thereof and it provides a separate compartment receiving the garbage so that such waste does not have to be stored or kept in the sink until it is carried out. Further, the keeping of the garbage in the hopper A as set forth will prevent food acids and other acids from the garbage from attacking or wearing the enamel surface of the sink. I believe that in my sink construction, the sink basin may be kept brighter and the finish thereon will wear longer than with the old forms of garbage disposal heretofore employed. Furthermore, where the garbage disposal is a part of the regular drain of the sink, I have found that garbage still is discharged into the main basin of the sink and thus shows a greater wear on the enameled surface of the same than where a separate hopper for the garbage is provided as I have illustrated herein.

A feature resides in providing a separate hopper for garbage waste matter separate from the drain of the sink and wherein the garbage may be reduced to a minimum of bulk by washing as soon as possible down the drain and without requiring a mechanical unit such as B where an economical form of garbage disposal and sink construction is desired. Yet, if circumstances permit and it is desired, mechanical garbage disposal device such as B may be readily used with my form of sink.

I have illustrated a new form and manner of disposal of the garbage in Figure 2 where the garbage bucket is positioned in the wall of the building and is accessible to the outside so the garbage collector can pick up the same without disturbing the occupants of the building and where the garbage may be discharged into a bucket concealed in the wall of the building. This form of garbage disposal means may be more desirable for warmer climates. However, the same can be insulated or even heated if it is desirable so that this means of garbage disposal may be used in any climate.

In Figure 8, I have illustrated the hopper A divided into a partition 35 so that on one side of the hopper garbage may be received and on the other side cans and other refuse may be placed. Cover 17 closes the hopper A in the same manner as described and illustrated in the other figures.

In Figure 9, I have illustrated the hopper A

positioned on the right hand side of the sink 10. Thus it will be apparent that these variations of construction may be employed.

While the drawings illustrate a particular form of construction of hopper formed as a part of the sink body 10, it is apparent that other designs and forms may be made within the scope of the following claims without departing from the spirit of this invention.

I claim:

1. A sink comprising a horizontal shelf and a basin extending downwardly from said shelf, said shelf including a rear portion having a swinging faucet extending upwardly therefrom and thence outwardly, said rear portion of said shelf also having a garbage hopper depending therefrom, said hopper being located adjacent said faucet so that the faucet may be swung into a position to discharge into the hopper, whereby garbage in said hopper may be washed and said hopper may be cleaned, said hopper having a peripheral flange extending around its lowermost edge where-

by the hopper may be connected to a garbage disposal unit or a drain.

2. A sink comprising a horizontal shelf and a basin extending downwardly from said shelf, said shelf including a rear portion having an opening therein adapted to receive a swinging faucet, that extends upwardly therefrom and thence outwardly, said rear portion of said shelf also having a garbage hopper depending therefrom, said hopper being located adjacent said faucet opening so that when a faucet is mounted in said opening, it may be swung into a position to discharge into the hopper, whereby garbage in said hopper may be washed and said hopper may be cleaned, said hopper having a peripheral flange extending around its lowermost edge whereby the hopper may be connected to a garbage disposal unit or a drain, said shelf, basin and hopper being integrally formed, whereby joints are eliminated between the hopper and the shelf.

VINCENT R. O'BRIEN.
